UNITED STATES PATENT OFFICE.

JOHN HENRY HUCKE, JR., OF NEW YORK, N. Y.

DESIGN FOR A FEED-BAG FOR HORSES.

47,519.

Specification for Design.

Patented June 29, 1915.

Application filed January 6, 1915. Serial No. 876. Term of patent 7 years.

To all whom it may concern:

Be it known that I, JOHN HENRY HUCKE, Jr., a citizen of the United States, and a resident of the city of New York, borough of Brooklyn, in the county of Kings and State of New York, have invented a new, original, and ornamental Design for Feed-Bags for Horses, of which the following is a specification, reference being had to the accompanying drawing, forming part thereof.

Figure 1 is a perspective view; and Fig. 2 is a front elevation, showing my new design.

I claim:

The ornamental design for a feed bag for horses, as shown.

JOHN HENRY HUCKE, Jr.
